United States Patent Office

Des. 196,157
Patented Aug. 27, 1963

196,157

AIRCRAFT

Frank A. Petry, 1615 Armacost Ave., Los Angeles, Calif.

Filed Mar. 5, 1962, Ser. No. 69,086

Term of patent 14 years

(Cl. D71—1)

Fig. 1

Fig. 2

Fig. 3

Fig. 4

FIG. 1 is a perspective view of an aircraft embodying my new design;

FIG. 2 is a top plan view thereof;

FIG. 3 is a side elevation thereof, the opposite side being a mirror image of this disclosed side; and

FIG. 4 is a front elevation of the aircraft, the rear being substantially the same in appearance thereto.

I claim:

The ornamental design for an aircraft, substantially as shown and described.
